Elihu Smith, Albany, N.Y.
Letters Patent No 849 Dated Nov: 11th 1851.

The schedule referred to in these Letters Patent and making part of the same.

To all whom it may concern:

Be it known that I, Elihu Smith, of the City of Albany, and State of New York, have produced a new and original ornamental design for the plates of a Parlor Stove, and I hereby declare that the annexed drawings, being part of this specification are full and accurate delineations of the plates constituting parts of the Stove with their ornamental parts. The back and end plates of the fire box and the side plate of the bracket legs of the fire box, not shewn in the drawings being symmetrically similar to the parts shown.

What I claim as my production and design to secure by Letters Patent is the combination and arrangement of ornamental figures and forms represented in the accompanying drawings forming the ornamental design for the plates of a parlor Stove as represented in the accompanying drawings.

Witnessed,

Richd Farick De Witt,
C. J. Miller,

Elihu Smith.
